UNITED STATES PATENT OFFICE.

JAMES RITCHIE, OF LITCHFIELD, ILLINOIS.

BUNDLE-DROPPER FOR GRAIN-BINDERS.

SPECIFICATION forming part of Letters Patent No. 390,401, dated October 2, 1888.

Application filed March 23, 1888. Serial No. 268,283. (No model.)

To all whom it may concern:

Be it known that I, JAMES RITCHIE, a citizen of the United States, residing at Litchfield, in the county of Montgomery and State 5 of Illinois, have invented a new and useful Improvement in Bundle-Droppers for Grain-Binders, of which the following is a specification.

This invention has reference to bundle-droppers for grain-binders; and it consists in the improved construction hereinafter described, whereby a simple and efficient arrangement is provided that will discharge the bundles from the side instead of rear, as in many prior constructions, the disposition of the dumping-platform and its connections being such that it may be readily elevated to enable the machine to be of minimum dimension in width when it is desired to pass through gate-openings, &c. The invention further consists in other features of construction set forth and explained.

In the accompanying drawings, forming part of this specification, Figure 1 is a perspective view of a dropper embodying my improvements. Fig. 2 is a rear view showing the dropper in an elevated position.

The vertical boards A A are secured to the horizontal beams Z Z, and are connected at 30 their inner and outer ends by the cross-bars a b. The boards A A and the beams Z Z form part of the main frame. The harvester and the extended portion of one of said beams Z form a support for the platform-carrying rod, 35 hereinafter referred to. Outwardly and upwardly inclined side standards, B, are secured to the sides of the boards A A, and are connected together at their upper ends by means of a horizontal cross-bar, C. On the outer 40 face of the cross-bar b are bearing-loops e, in which is mounted the straight end of the horizontal inner portion, d, of the platform-carrying rod D.

The rod D is a continuous rod, of proper 45 size and material, having the inner portion, d, just referred to, the straight outwardly-extending portion d', leading from the rear end of said inner portion, and the straight outer portion, d'', nearly parallel with the portion d, 50 but diverging slightly therefrom, as shown in

dotted lines in Fig. 1. When the carrying-rod is in its lowered position, the outwardly-projecting portion d' rests upon and is supported by the projecting end of the rear beam, Z, thereby relieving the strain on the rod K. 55

The dumping-platform consists of a flat metal bar, e, which has its sides provided with re-enforcing flanges, to strengthen the same and secure rigidity, and its ends bent down and perforated for the reception of the portion 60 d' of the platform-carrying rod, and the parallel slats or boards E, E', and E'', spaced and laid transversely to the bar e and secured thereto, forming the platform proper.

The slats E' E'' have their outer ends turned 65 up to form inclined stops f, and a small vertical strip, f'', is secured to these stops and extends between the same for the sheaves to bear against and prevent their accidental rolling from the platform. The slat E' is shorter than the slat E'', so that the vertical strip f'' extends inward toward the front side of the machine, as clearly shown. The slat or board E is provided with a series of slots for the passage of the shattered grain. One of the ends, 75 70 e', of the bar e has secured thereto a bracket-arm, f', the vertical portion of the free end of which is perforated for the engagement of the hooked end of a rod, F, the inner end of which is connected pivotally to the outer horizontally-bent end, g, of a horizontal connecting rod or link, G. This construction permits the swinging of the rod F upon its pivotal connection with the rod or link G when the platform is raised, as will be understood. I also 80 by this means provide for a swinging motion of one of the parts and an endwise sliding movement of the other without binding or an excess of friction. 85

An angle-arm, H, has a horizontal portion, 90 h, bearing in the adjacent board, A, and its inner part is bent horizontally for the pivotal attachment of the other end of the link G. On the upper side of the cross-bar a is located a staple, i, which forms the fulcrum for a bell-crank lever, I, looped at its elbow to move freely upon said staple i, and having its longer or near end connected pivotally by a link, J, to the outer end of the angle-arm H. The employment of this angle-arm H insures the 95 100

proper operation of the connecting-rod G. Were the link J connected directly to the connecting-rod G, when the pedal was operated, the inner end of the said rod G would simply 5 be lowered without imparting any sliding movement to the outer end thereof; but by the arrangement shown, when the pedal is operated and the link depressed, the angle-arm will be first acted on and caused to swing, 10 and will in turn act on the rod G, swinging its inner end and causing its outer end to slide in a bracket, M, hereinafter referred to.

The free or front end of the bell-crank lever is bent laterally and horizontally to form a 15 pedal, j, or may have a pedal-plate attached thereto. Connected to the side of the rod D, adjacent to its outer portion, d', is a jointed rod, K, which extends through an eye, k, on the side of the upper portion of one of the 20 inclined side standards, B, near its upper and outer end, and terminates at its one end in a loop, k', which is designed for a handle for the driver. The rod K is jointed at k', and is provided in its outer joint with a guide-loop, 25 l, through which the rod F passes. This jointed construction of the rod K gives to it a slight flexibility, which is very desirable, and is also advantageous, for the reason that when the platform is raised, as shown in Fig. 2, the 30 inner joint will hang vertically, as shown, and by its weight will aid in maintaining the platform in its raised position. The end g of the link or connecting-rod G engages in between the horizontal guide portions m of a horizontal 35 wire bracket, M, extending along the rear side and secured to the outer end of the adjacent board, A. This bracket, as before stated, serves to guide the outer end of the connecting-rod G in its horizontal motion. Each of 40 the parallel side or end plates L' of the binder-frame is secured at its inner end to the inner side of each one of the side standards, B, and said plates are connected together at their outer ends by means of a cross-bar, N, 45 having depending from its under side a series of vertical hangers, h', which extend below the inner side of the dropper and serve to prevent bundle rolling off the platform toward the machine. The lower ends of these hangers 50 are bent outward to form supports h² for the inner edge of the carrying-platform when the same is lowered.

When the parts are in the position shown in Fig. 1, the sheaves pass from the binding 55 table or frame onto the platform of the dropper, the stops f of the same and the hangers h' insuring the proper retention of the bundles thereon. In its normal position the platform rests, as seen in Fig. 1, on the supports h² of 60 the hangers h' and on the outer portion, d', of the carrying-rod. In operation the driver keeps his foot on the pedal to hold the platform from tilting by the weight of the bundles thereon. When the foot is lifted, the platform 65 is tilted, as will be readily understood, the latter in tilting drawing with it the rods F

and G and the bell-crank lever I. Upon again depressing the pedal the rods F and G and their connections will be acted on to return the platform to its normal position.

70

The jointed rod K is provided for the purpose of raising the platform up over the side plates of the binder-frame of the machine out of the way when not in use, as is shown in Fig. 2. This jointed rod also serves to maintain the platform in its raised position, as the inner joint hangs vertically, as shown in Fig. 2, and as before described, and any downward motion of the platform will serve to draw said inner joint up across the eye k, when it will 80 act as a stop to prevent further motion, and the platform can be lowered only by raising said inner joint and allowing it to pass through the said eye k.

85

The stops f partially stop or retard the butt-ends of the sheaves when they are being discharged, so that the head will be advanced beyond the butts. The sheaves will thus be caused to fall on their head ends, while the butt-ends will be carried over by the impetus, 90 so that the sheaves will be carried farther from the travel of the machine than they would be if the stops were not provided.

95

A sack or pouch, O, is arranged under the platform-frame of the dropper, and is secured, in any suitable manner, to the boards or slats thereof, in position to receive the shattered grain which passes through the spaces between the slats E E' E² and through the slots x x in the slat E.

100

It will be understood, of course, that the driver keeps the pedal normally depressed by his foot, thereby preventing undue movement of the rods G and F and tilting of the platform.

I claim—

105

1. The combination of the boards A A, the bar b, connecting the outer ends of the same, the platform-carrying rod D, having an outer portion, d', and an inner portion, d, pivoted to the said bar b, a tilting platform mounted 110 on the outer portion, d', of the rod D, means for raising the said rod, and pivotally-connected rods operated by the pedal to tilt the platform, as set forth.

115

2. The combination, with the boards A A and the bar b, connecting the outer ends of the same, of the carrying-rod having an inner portion, d, pivoted on the bar b, and provided with an outer portion, d', the tilting platform mounted on the said outer portion, d', of the 120 rod D, means for tilting the platform, a standard rising from one of the boards A, an eye on said standard, and a jointed rod connected to the carrying-rod and passing through said eye to raise said platform and to maintain it 125 raised, as set forth.

130

3. The combination, with the main frame, of the carrying-rod pivoted thereto and having an outer portion, d', the tilting platform mounted on said outer portion, d', of the carrying-rod, the stops f at the front outer edge of 135 the platform, means for raising the carrying-

rod, and means for tilting the platform, as set forth.

4. The combination of the main frame, the carrying-rod pivoted thereto, the platform mounted thereon, means for raising said rod, the guide-bracket on the main frame, the rod F, connected to the platform, the rod G, connected to the rod F and engaging the guide-bracket, the angle-arm H, connected to the rod,

and the pedal connected to the arm H, as so specified.

In testimony that I claim the foregoing as my own I have hereto affixed my signature in presence of two witnesses.

JAMES RITCHIE.
